CLAIM

The ornamental design for a tool handle, as shown and
described.

DESCRIPTION

FIG. 1 is a top plan view of a tool handle showing our new
design, with the broken lines being for illustrative purposes
only and forming no part of the claimed design;

FIG. 2 is a side elevational view of thereof;

FIG. 3 is a front end elevational view thereof;

FIG. 4 is a rear end elevational view thereof;

FIG. 5 is a bottom plan view thereof; and,

FIG. 6 is an elevational view of the side opposite that shown
in FIG. 2.
